US0D1057861S

(12) **United States Design Patent** (10) Patent No.: **US D1,057,861 S**
(45) Date of Patent: ** Jan. 14, 2025

(54) **PEDAL EXERCISER**

(71) Applicant: **Jiaolong Li**, Sichuan (CN)

(72) Inventor: **Jiaolong Li**, Sichuan (CN)

(**) Term: **15 Years**

(21) Appl. No.: **29/960,893**

(22) Filed: **Sep. 3, 2024**

(51) LOC (15) Cl. **21-02**

(52) U.S. Cl.

USPC **D21/663**; D21/670

(58) **Field of Classification Search**

USPC D21/662, 663, 664, 666, 668, 670, 697
CPC A63B 22/0046; A63B 22/06; A63B
23/03541; A63B 21/0628; A63B 21/4047;
A63B 23/1209

Primary Examiner — Mojtaba Tehrani

(57) **CLAIM**

The ornamental design for a pedal exerciser, as shown and described.

DESCRIPTION

FIG. 1 is a perspective view of a pedal exerciser showing the new design;

FIG. 2 is another perspective view thereof;

FIG. 3 is a front elevation view thereof;

FIG. 4 is a back elevation view thereof;

FIG. 5 is a left side elevation view thereof;

FIG. 6 is a right side elevation view thereof;

FIG. 7 is a top plan view thereof; and,

FIG. 8 is a bottom plan view thereof.

1 Claim, 8 Drawing Sheets
